UNITED STATES PATENT OFFICE.

LEE C. SHARP, OF PLATTSMOUTH, NEBRASKA, ASSIGNOR TO FRANZ BRÜCKMANN, JR.,
OF BRUNSWICK, GERMANY.

MEANS FOR CAPPING AND PERFORMING OTHER OPERATIONS ON CANS.

996,531.

Specification of Letters Patent. Patented June 27, 1911.

Application filed March 8, 1907. Serial No. 361,311.

To all whom it may concern:

Be it known that I, LEE C. SHARP, of the city of Plattsouth, in the county of Cass and State of Nebraska, have invented certain new and useful Improvements in Means for Capping and Performing other Operations on Cans, of which the following is a full, clear, and exact specification, such as will enable others skilled in the art to which it appertains to make and use the same.

A special, though not the sole, object of my invention is to provide a machine by means of which the covers may be secured on cans when the cans are in upright position thus allowing the cans to be filled first with liquid or semi liquid contents and the cover applied hermetically without spilling the contents of the can.

My invention is especially adapted to fastening the covers by what is termed a roll seam which so firmly clamps together the cover and can body as to prevent the necessity of solder or other sealing substance in many cases.

My invention also involves novel mechanism by which the seams may be soldered, if it is so desired, and by means of which various other operations may be performed on the cans.

My invention further involves certain improvements in the devices for rolling the seam either inward or outward and for insuring a hermetic connection without subjecting the body of the can to undue strain.

My invention involves various other features of major or minor importance and all of them will be fully set forth hereinafter and particularly pointed out in the claims.

Reference is now had to the accompanying drawings which illustrate, as an example, one embodiment of my invention with certain modifications in the devices for forming the seam, in which drawings,

Figure 1 is a sectional elevation of the machine fitted with devices for rolling the seam inward; Fig. 2 is an elevational view with parts in section showing the machine fitted with devices for rolling the seam outward; Fig. 3 is a sectional plan showing the mechanism for rotating the table; Fig. 4 is an enlarged detail showing the action of the crimping rollers on the seam and illustrat-

ing the novel relation of said rollers to the seam sustaining ring or belt; Fig. 5 is an enlarged section showing the seam supporting ring and the position which the same bears to the seam before the clamping operation; and Fig. 6 is a detail of the devices shown in Fig. 2 for rolling the seam outward.

Referring first to Figs. 1, 3, 4, and 5, 10, 15, 20, 25, 30, 35, 40, 45, 50, 55, 60, 65, 70, 75, 80, 85, 90, 95, 100, 105, 110, 115, 120, 125, 130, 135, 140, 145, 150, 155, 160, 165, 170, 175, 180, 185, 190, 195, 200, 205, 210, 215, 220, 225, 230, 235, 240, 245, 250, 255, 260, 265, 270, 275, 280, 285, 290, 295, 300, 305, 310, 315, 320, 325, 330, 335, 340, 345, 350, 355, 360, 365, 370, 375, 380, 385, 390, 395, 400, 405, 410, 415, 420, 425, 430, 435, 440, 445, 450, 455, 460, 465, 470, 475, 480, 485, 490, 495, 500, 505, 510, 515, 520, 525, 530, 535, 540, 545, 550, 555, 560, 565, 570, 575, 580, 585, 590, 595, 600, 605, 610, 615, 620, 625, 630, 635, 640, 645, 650, 655, 660, 665, 670, 675, 680, 685, 690, 695, 700, 705, 710, 715, 720, 725, 730, 735, 740, 745, 750, 755, 760, 765, 770, 775, 780, 785, 790, 795, 800, 805, 810, 815, 820, 825, 830, 835, 840, 845, 850, 855, 860, 865, 870, 875, 880, 885, 890, 895, 900, 905, 910, 915, 920, 925, 930, 935, 940, 945, 950, 955, 960, 965, 970, 975, 980, 985, 990, 995, 1000, 1005, 1010, 1015, 1020, 1025, 1030, 1035, 1040, 1045, 1050, 1055, 1060, 1065, 1070, 1075, 1080, 1085, 1090, 1095, 1100, 1105, 1110, 1115, 1120, 1125, 1130, 1135, 1140, 1145, 1150, 1155, 1160, 1165, 1170, 1175, 1180, 1185, 1190, 1195, 1200, 1205, 1210, 1215, 1220, 1225, 1230, 1235, 1240, 1245, 1250, 1255, 1260, 1265, 1270, 1275, 1280, 1285, 1290, 1295, 1300, 1305, 1310, 1315, 1320, 1325, 1330, 1335, 1340, 1345, 1350, 1355, 1360, 1365, 1370, 1375, 1380, 1385, 1390, 1395, 1400, 1405, 1410, 1415, 1420, 1425, 1430, 1435, 1440, 1445, 1450, 1455, 1460, 1465, 1470, 1475, 1480, 1485, 1490, 1495, 1500, 1505, 1510, 1515, 1520, 1525, 1530, 1535, 1540, 1545, 1550, 1555, 1560, 1565, 1570, 1575, 1580, 1585, 1590, 1595, 1600, 1605, 1610, 1615, 1620, 1625, 1630, 1635, 1640, 1645, 1650, 1655, 1660, 1665, 1670, 1675, 1680, 1685, 1690, 1695, 1700, 1705, 1710, 1715, 1720, 1725, 1730, 1735, 1740, 1745, 1750, 1755, 1760, 1765, 1770, 1775, 1780, 1785, 1790, 1795, 1800, 1805, 1810, 1815, 1820, 1825, 1830, 1835, 1840, 1845, 1850, 1855, 1860, 1865, 1870, 1875, 1880, 1885, 1890, 1895, 1900, 1905, 1910, 1915, 1920, 1925, 1930, 1935, 1940, 1945, 1950, 1955, 1960, 1965, 1970, 1975, 1980, 1985, 1990, 1995, 2000, 2005, 2010, 2015, 2020, 2025, 2030, 2035, 2040, 2045, 2050, 2055, 2060, 2065, 2070, 2075, 2080, 2085, 2090, 2095, 2100, 2105, 2110, 2115, 2120, 2125, 2130, 2135, 2140, 2145, 2150, 2155, 2160, 2165, 2170, 2175, 2180, 2185, 2190, 2195, 2200, 2205, 2210, 2215, 2220, 2225, 2230, 2235, 2240, 2245, 2250, 2255, 2260, 2265, 2270, 2275, 2280, 2285, 2290, 2295, 2300, 2305, 2310, 2315, 2320, 2325, 2330, 2335, 2340, 2345, 2350, 2355, 2360, 2365, 2370, 2375, 2380, 2385, 2390, 2395, 2400, 2405, 2410, 2415, 2420, 2425, 2430, 2435, 2440, 2445, 2450, 2455, 2460, 2465, 2470, 2475, 2480, 2485, 2490, 2495, 2500, 2505, 2510, 2515, 2520, 2525, 2530, 2535, 2540, 2545, 2550, 2555, 2560, 2565, 2570, 2575, 2580, 2585, 2590, 2595, 2600, 2605, 2610, 2615, 2620, 2625, 2630, 2635, 2640, 2645, 2650, 2655, 2660, 2665, 2670, 2675, 2680, 2685, 2690, 2695, 2700, 2705, 2710, 2715, 2720, 2725, 2730, 2735, 2740, 2745, 2750, 2755, 2760, 2765, 2770, 2775, 2780, 2785, 2790, 2795, 2800, 2805, 2810, 2815, 2820, 2825, 2830, 2835, 2840, 2845, 2850, 2855, 2860, 2865, 2870, 2875, 2880, 2885, 2890, 2895, 2900, 2905, 2910, 2915, 2920, 2925, 2930, 2935, 2940, 2945, 2950, 2955, 2960, 2965, 2970, 2975, 2980, 2985, 2990, 2995, 3000, 3005, 3010, 3015, 3020, 3025, 3030, 3035, 3040, 3045, 3050, 3055, 3060, 3065, 3070, 3075, 3080, 3085, 3090, 3095, 3100, 3105, 3110, 3115, 3120, 3125, 3130, 3135, 3140, 3145, 3150, 3155, 3160, 3165, 3170, 3175, 3180, 3185, 3190, 3195, 3200, 3205, 3210, 3215, 3220, 3225, 3230, 3235, 3240, 3245, 3250, 3255, 3260, 3265, 3270, 3275, 3280, 3285, 3290, 3295, 3300, 3305, 3310, 3315, 3320, 3325, 3330, 3335, 3340, 3345, 3350, 3355, 3360, 3365, 3370, 3375, 3380, 3385, 3390, 3395, 3400, 3405, 3410, 3415, 3420, 3425, 3430, 3435, 3440, 3445, 3450, 3455, 3460, 3465, 3470, 3475, 3480, 3485, 3490, 3495, 3500, 3505, 3510, 3515, 3520, 3525, 3530, 3535, 3540, 3545, 3550, 3555, 3560, 3565, 3570, 3575, 3580, 3585, 3590, 3595, 3600, 3605, 3610, 3615, 3620, 3625, 3630, 3635, 3640, 3645, 3650, 3655, 3660, 3665, 3670, 3675, 3680, 3685, 3690, 3695, 3700, 3705, 3710, 3715, 3720, 3725, 3730, 3735, 3740, 3745, 3750, 3755, 3760, 3765, 3770, 3775, 3780, 3785, 3790, 3795, 3800, 3805, 3810, 3815, 3820, 3825, 3830, 3835, 3840, 3845, 3850, 3855, 3860, 3865, 3870, 3875, 3880, 3885, 3890, 3895, 3900, 3905, 3910, 3915, 3920, 3925, 3930, 3935, 3940, 3945, 3950, 3955, 3960, 3965, 3970, 3975, 3980, 3985, 3990, 3995, 4000, 4005, 4010, 4015, 4020, 4025, 4030, 4035, 4040, 4045, 4050, 4055, 4060, 4065, 4070, 4075, 4080, 4085, 4090, 4095, 4100, 4105, 4110, 4115, 4120, 4125, 4130, 4135, 4140, 4145, 4150, 4155, 4160, 4165, 4170, 4175, 4180, 4185, 4190, 4195, 4200, 4205, 4210, 4215, 4220, 4225, 4230, 4235, 4240, 4245, 4250, 4255, 4260, 4265, 4270, 4275, 4280, 4285, 4290, 4295, 4300, 4305, 4310, 4315, 4320, 4325, 4330, 4335, 4340, 4345, 4350, 4355, 4360, 4365, 4370, 4375, 4380, 4385, 4390, 4395, 4400, 4405, 4410, 4415, 4420, 4425, 4430, 4435, 4440, 4445, 4450, 4455, 4460, 4465, 4470, 4475, 4480, 4485, 4490, 4495, 4500, 4505, 4510, 4515, 4520, 4525, 4530, 4535, 4540, 4545, 4550, 4555, 4560, 4565, 4570, 4575, 4580, 4585, 4590, 4595, 4600, 4605, 4610, 4615, 4620, 4625, 4630, 4635, 4640, 4645, 4650, 4655, 4660, 4665, 4670, 4675, 4680, 4685, 4690, 4695, 4700, 4705, 4710, 4715, 4720, 4725, 4730, 4735, 4740, 4745, 4750, 4755, 4760, 4765, 4770, 4775, 4780, 4785, 4790, 4795, 4800, 4805, 4810, 4815, 4820, 4825, 4830, 4835, 4840, 4845, 4850, 4855, 4860, 4865, 4870, 4875, 4880, 4885, 4890, 4895, 4900, 4905, 4910, 4915, 4920, 4925, 4930, 4935, 4940, 4945, 4950, 4955, 4960, 4965, 4970, 4975, 4980, 4985, 4990, 4995, 5000, 5005, 5010, 5015, 5020, 5025, 5030, 5035, 5040, 5045, 5050, 5055, 5060, 5065, 5070, 5075, 5080, 5085, 5090, 5095, 5100, 5105, 5110, 5115, 5120, 5125, 5130, 5135, 5140, 5145, 5150, 5155, 5160, 5165, 5170, 5175, 5180, 5185, 5190, 5195, 5200, 5205, 5210, 5215, 5220, 5225, 5230, 5235, 5240, 5245, 5250, 5255, 5260, 5265, 5270, 5275, 5280, 5285, 5290, 5295, 5300, 5305, 5310, 5315, 5320, 5325, 5330, 5335, 5340, 5345, 5350, 5355, 5360, 5365, 5370, 5375, 5380, 5385, 5390, 5395, 5400, 5405, 5410, 5415, 5420, 5425, 5430, 5435, 5440, 5445, 5450, 5455, 5460, 5465, 5470, 5475, 5480, 5485, 5490, 5495, 5500, 5505, 5510, 5515, 5520, 5525, 5530, 5535, 5540, 5545, 5550, 5555, 5560, 5565, 5570, 5575, 5580, 5585, 5590, 5595, 5600, 5605, 5610, 5615, 5620, 5625, 5630, 5635, 5640, 5645, 5650, 5655, 5660, 5665, 5670, 5675, 5680, 5685, 5690, 5695, 5700, 5705, 5710, 5715, 5720, 5725, 5730, 5735, 5740, 5745, 5750, 5755, 5760, 5765, 5770, 5775, 5780, 5785, 5790, 5795, 5800, 5805, 5810, 5815, 5820, 5825, 5830, 5835, 5840, 5845, 5850, 5855, 5860, 5865, 5870, 5875, 5880, 5885, 5890, 5895, 5900, 5905, 5910, 5915, 5920, 5925, 5930, 5935, 5940, 5945, 5950, 5955, 5960, 5965, 5970, 5975, 5980, 5985, 5990, 5995, 6000, 6005, 6010, 6015, 6020, 6025, 6030, 6035, 6040, 6045, 6050, 6055, 6060, 6065, 6070, 6075, 6080, 6085, 6090, 6095, 6100, 6105, 6110, 6115, 6120, 6125, 6130, 6135, 6140, 6145, 6150, 6155, 6160, 6165, 6170, 6175, 6180, 6185, 6190, 6195, 6200, 6205, 6210, 6215, 6220, 6225, 6230, 6235, 6240, 6245, 6250, 6255, 6260, 6265, 6270, 6275, 6280, 6285, 6290, 6295, 6300, 6305, 6310, 6315, 6320, 6325, 6330, 6335, 6340, 6345, 6350, 6355, 6360, 6365, 6370, 6375, 6380, 6385, 6390, 6395, 6400, 6405, 6410, 6415, 6420, 6425, 6430, 6435, 6440, 6445, 6450, 6455, 6460, 6465, 6470, 6475, 6480, 6485, 6490, 6495, 6500, 6505, 6510, 6515, 6520, 6525, 6530, 6535, 6540, 6545, 6550, 6555, 6560, 6565, 6570, 6575, 6580, 6585, 6590, 6595, 6600, 6605, 6610, 6615, 6620, 6625, 6630, 6635, 6640, 6645, 6650, 6655, 6660, 6665, 6670, 6675, 6680, 6685, 6690, 6695, 6700, 6705, 6710, 6715, 6720, 6725, 6730, 6735, 6740, 6745, 6750, 6755, 6760, 6765, 6770, 6775, 6780, 6785, 6790, 6795, 6800, 6805, 6810, 6815, 6820, 6825, 6830, 6835, 6840, 6845, 6850, 6855, 6860, 6865, 6870, 6875, 6880, 6885, 6890, 6895, 6900, 6905, 6910, 6915, 6920, 6925, 6930, 6935, 6940, 6945, 6950, 6955, 6960, 6965, 6970, 6975, 6980, 6985, 6990, 6995, 7000, 7005, 7010, 7015, 7020, 7025, 7030, 7035, 7040, 7045, 7050, 7055, 7060, 7065, 7070, 7075, 7080, 7085, 7090, 7095, 7100, 7105, 7110, 7115, 7120, 7125, 7130, 7135, 7140, 7145, 7150, 7155, 7160, 7165, 7170, 7175, 7180, 7185, 7190, 7195, 7200, 7205, 7210, 7215, 7220, 7225, 7230, 7235, 7240, 7245, 7250, 7255, 7260, 7265, 7270, 7275, 7280, 7285, 7290, 7295, 7300, 7305, 7310, 7315, 7320, 7325, 7330, 7335, 7340, 7345, 7350, 7355, 7360, 7365, 7370, 7375, 7380, 7385, 7390, 7395, 7400, 7405, 7410, 7415, 7420, 7425, 7430, 7435, 7440, 7445, 7450, 7455, 7460, 7465, 7470, 7475, 7480, 7485, 7490, 7495, 7500, 7505, 7510, 7515, 7520, 7525, 7530, 7535, 7540, 7545, 7550, 7555, 7560, 7565, 7570, 7575, 7580, 7585, 7590, 7595, 7600, 7605, 7610, 7615, 7620, 7625, 7630, 7635, 7640, 7645, 7650, 7655, 7660, 7665, 7670, 7675, 7680, 7685, 7690, 7695, 7700, 7705, 7710, 7715, 7720, 7725, 7730, 7735, 7740, 7745, 7750, 7755, 7760, 7765, 7770, 7775, 7780, 7785, 7790, 7795, 7800, 7805, 7810, 7815, 7820, 7825, 7830, 7835, 7840, 7845, 7850, 7855, 7860, 7865, 7870, 7875, 7880, 7885, 7890, 7895, 7900, 7905, 7910, 7915, 7920, 7925, 7930, 7935, 7940, 7945, 7950, 7955, 7960, 7965, 7970, 7975, 7980, 7985, 7990, 7995, 8000, 8005, 8010, 8015, 8020, 8025, 8030, 8035, 8040, 8045, 8050, 8055, 8060, 8065, 8070, 8075, 8080, 8085, 8090, 8095, 8100, 8105, 8110, 8115, 8120, 8125, 8130, 8135, 8140, 8145, 8150, 8155, 8160, 8165, 8170, 8175, 8180, 8185, 8190, 8195, 8200, 8205, 8210, 8215, 8220, 8225, 8230, 8235, 8240, 8245, 8250, 8255, 8260, 8265, 8270, 8275, 8280, 8285, 8290, 8295, 8300, 8305, 8310, 8315, 8320, 8325, 8330, 8335, 8340, 8345, 8350, 8355, 8360, 8365, 8370, 8375, 8380, 8385, 8390, 8395, 8400, 8405, 8410, 8415, 8420, 8425, 8430, 8435, 8440, 8445, 8450, 8455, 8460, 8465, 8470, 8475, 8480, 8485, 8490, 8495, 8500, 8505, 8510, 8515, 8520, 8525, 8530, 8535, 8540, 8545, 8550, 8555, 8560, 8565, 8570, 8575, 8580, 8585, 8590, 8595, 8600, 8605, 8610, 8615, 8620, 8625, 8630, 8635, 8640, 8645, 8650, 8655, 8660, 8665, 8670, 8675, 8680, 8685, 8690, 8695, 8700, 8705,

jecting from the base 10. The upper end of the shaft 29 has fastened thereto a crank disk 31 on the pin 32 of which a collar 33 is loosely mounted. To this collar 33 a link 34 is pivoted and this link is in turn pivoted to a collar 35 mounted loosely on a pin 36 secured to a slide 37. This slide is arranged to run freely in an annular pocket 38 formed in the table 17, and mounted on the slide is a spring pressed pawl 39 engaging a ratchet tooth 40 formed on the outer wall of the pocket 38. It will be seen, therefore, that upon rotation of the shaft 20 the table is given a regular up and down motion and also that, through the parts 27, 28, 29, 31, and 34, the table is given a regular step by step rotation. The pivotal connection of the link 34 with the swivel collars 33 and 35 allows this step by step rotation to be imparted to the table notwithstanding its vertical motion and by properly proportioning the parts the movements imparted to the table may be rendered exact and regular. The vertical movement of the table is intended to engage and disengage the cans with the devices for capping and otherwise operating thereon, and the rotary movement is intended to advance the cans from one step of the operation to the other.

The rigid column 11 carries intermediate its ends a spider 41 adapted to support the devices for crimping, fluxing, soldering or for performing various other operations on the cans. According to the structure shown in Fig. 1 the spider has four arms, of which three designated 41^a, 41^b, and 41^c are shown in Fig. 1. According to the structure shown in Fig. 2 the spider has two arms designated 41^d and 41^e. In Fig. 1 the arm 41^a is illustrated as sustaining a device for forming a seam by clamping or rolling the flanges of the head and cover inward; the arm 41^b is illustrated as sustaining a brush for supplying flux to the seam; the arm 41^c is illustrated as sustaining a soldering device. In Fig. 2 the arms 41^d and 41^e are both illustrated as sustaining devices for forming the seam by rolling the flanges outward. I desire it distinctly understood that the invention is in no sense limited to the devices above referred to, and that it may be fitted with various tools and implements for performing various other operations on cans and similar articles.

Again referring to Fig. 1, 42 indicates a rotating spindle which carries a band wheel 43 over which a belt 44 runs to impart to the spindle continuous rotary motion. This belt passes around idler pulleys 45 carried on an arm 46^a of a spider 46 secured to the top of the column 11. The spider 46 as here shown has four arms of which three are visible in the Fig. 1, 46^a, 46^b, and 46^c. The upper part of the spindle 42 is carried in the arm 46^c and the lower part of the spindle

projects downward through a box in the arm 41^a of the spindle 41. At its lower extremity said spindle carries a crimping head 47 provided with crimping rollers 48 acting on the flanges of the can body and head and serving to roll inward the seam as will be fully set forth hereinafter. A frusto-conical cam 49 is secured to the spindle 42 above the spider 41 and this cam is adapted to act on rollers 50 mounted on the upper ends of four levers 51 pivoted at equidistant points from each other on pins 52 carried by the arm 41^a of the spider 41. These levers 51 respectively carry at their lower ends quadrants 53 which match to form a box-like enclosure for the crimping head 47. Said quadrants 53 carry respectively the four quadrants of a ring 54 which is adapted to embrace the can during the crimping operation and which is provided with an anvil ring 55 adapted to lie under the seam during the crimping operation. This ring 55 is also in four quadrant shaped sections respectively carried by the quadrants 54. The arm 46^c of the spider 46 has mounted thereon a lever 56 which has a connection 57 with the spindle 42 by means of which vertical reciprocation may be imparted to the spindle. The inner end of the lever 56 is connected to a rod 58 which extends down through the hollow column and is provided with two rollers 59 engaging opposite sides of the cam 60 fastened to a shaft 20. It will be seen, therefore, that the spindle 42, notwithstanding its continuous rotation, is by the devices 56, 58 and 60, given a regular up and down motion bringing the crimping rolls 48 into engagement with the seam, and also by the action of the cam 49, throwing inward the lower ends of the levers 51 and causing the quadrants 53 and 54 to close around the crimping head and the upper part of the can, with the result that the anvil ring is pressed snugly under the seam to back and sustain the same during the crimping operation, preventing the can from collapsing under the pressure of the crimping rollers. The instant that the spindle 42 rises and the cam 49 disengages the roller 50, the quadrants 53 and 54 disengage the can and allow it to drop with the table out of engagement with the crimping devices. If necessary suitable springs may be applied to assist this disengaging action of the quadrants.

Referring particularly to Figs. 4 and 5, which show enlarged details of the crimping devices it will be seen that the spindle 42 carries the crimping head 47 through the medium of a loose pin 61 allowing the head 47 to have a limited gyrating movement on the spindle. Interposed between a collar 62 on the spindle and the head 47 is a rubber pad 63 which sustains the head firmly, but at the same time allows it to yield to adapt

itself to any slight disarrangement of the cam and thus avoids crushing the can. In Fig. 5 the can and cover are shown in section, *a* indicating the can and *b* its cover. 5 This view also shows that the body *a* of the can is provided with an outward and upwardly extending flange *a'* and that the cover *b* is provided with an upwardly extending flange *b'* which lies inside of the 10 flange *a'*. As the sections of the anvil ring 55 close around the can by the operation before described, they assume, as shown in Fig. 5, a position directly under the outwardly disposed part of the flange *a'* the 15 anvil ring snugly engaging the sides of the can body adjacent to this flange. It will be seen that this ring, therefore, forms a rigid support for the seam of the can during the crimping operation and by referring to Fig. 20 4, it may be seen that the crimping rollers 48 operating to turn or roll the flanges *a'* and *b'* inward to form the seam, exert their pressure directly against the anvil ring enabling the seam to be formed under great 25 pressure insuring a hermetic joint and avoiding subjecting the body of the can to any collapsing strain. The important principle of this feature of my invention is the outward flanging of the can body producing 30 a shoulder under which the anvil ring 55 may lie so that the roll seam may be formed directly opposite the anvil ring and hence subjected to that pressure which is necessary to form the seam effectually without, however, 35 destroying or straining the can body.

In Fig. 2 the spindle 42 does not rotate but is merely vertically movable by the mechanism before described for this purpose. The crimping rollers 64 in Fig. 2 are 40 arranged to roll the seam outward and downward for which purpose the can and cover are provided with outward or horizontal flanges. Said crimping rollers 64 rotate around their own axes and are carried 45 to move bodily around the axis of the shaft or spindle 42 by means of levers 65. These levers have slide ways 66 formed at their lower ends and the rollers 64 are mounted on slides 67 which are adjustable in the 50 slideways and held by means of set screws passing through the side walls of the slide ways and engaging the slides. The levers 65 are fulcrumed within a pulley 68, the hub 69 whereof is rotatable around the 55 spindle or shaft 42 and bears on the crimping head 70 which is secured to the lower end of the spindle. As the spindle descends to engage the head in the cavity in the top of the can, the levers 65 actuated by the cam 60 71 on the spindle are moved so that their under ends carry the crimping rollers into engagement with the flanges of the can body and head. A belt is arranged to drive the pulley 68, and as the crimping rollers move 65 around the can they form the roll seam.

Fig. 2 shows two crimping devices one at one side and one at the other side of the column 11, these devices being duplicates of each other. Fig. 6 shows the details concerned with the formation of the outwardly crimped seam. The crimping head 70 of the spindle 42 is formed with a peripheral groove 72 and the crimping rollers 64 have at their upper ends flanges 73 which fit in the groove 72. Since the crimping operation involves a thrust on the crimping roller in the direction of the arrow indicated in Fig. 6, this engagement of the flange 73 in the groove 72 causes the thrust to be communicated to the head 70 and the center pin 75 of the roller is thereby saved from strain. Further by forming this engagement between the crimping roller and head the flange of the can top is prevented from being swaged inward and the formation of 80 a wire edge at this point is prevented. Heretofore in the formation of seams of this sort the flange has been crowded in at the inside of the seam and a sharp edge left which not only is dangerous in the handling of 85 the can but which also prevents the formation of a tight seam. The body *a* of the can is as shown in Fig. 2, formed first with an outward flange *a'* and the cover or top *b* of the can is formed with an upwardly extending flange *b'* the cover being depressed into the body as shown in Fig. 2. The crimping head when it engages the cover is received in the cavity in the top thereof and the crimping roller acts against the flanges and 90 rolls the same down into a seam as indicated in Fig. 6.

In Fig. 1, 74 may be taken to indicate for example, a brush for applying the flux to the seam of the can and 75 a soldering iron 105 heated by a gas burner 76. The brush 74 is carried by a spindle 77 and the iron 75 by a spindle 78 which is preferably hollow to conduct the gas to the burner 76. The spindles 77 and 78 are mounted in boxes 110 on the spider arms 41^b, 46^b and 41^c and 46^a respectively and they are rotated by means of chain gearing 79 and 80, from the spindle 42, the chain gearing 79 having sufficient slack therein to allow the above described 115 vertical movement of the spindle. As before indicated the specific nature and function of the devices 74 and 75 are in no sense essential to my invention; the machine may be adapted to perform various other operations on the can or other article operated on.

In the operation of the machine as a whole, assuming for example, that it was used to cap, flux and solder full cans, upon the rotation of the shaft 20 the table 17 is 125 given a regular step by step rotary movement combined with a vertical movement. The operator has nothing to do but to place the full cans with the covers resting loosely thereon in the pockets 19 in the table as 130

these pockets are successively presented. As the can passes to the crimping device, the table raises the can into the space inclosed by the quadrants 53 and 54. At this time 5 the spindle 42 descends engaging the crimping rollers with the flanges of the can body and head and simultaneously closing the anvil ring around the can body under the flange α' thereof (see Fig. 5). The crimper 10 head rotating the rollers 48 around the flanges rolls the flanges in, forming a roll seam as illustrated in Fig. 4, the anvil ring 55 backing the operation of the crimping rollers as before explained. The anvil ring 15 then opens and the crimper head ascends simultaneously with the dropping of the table, disengaging the can from the crimping device. The table is then given another forward step and the can previously crimped 20 is brought under the fluxing brush 74. Flux may be supplied to this brush in any desired manner for example through a longitudinal passage in the shaft 77. The table then rises engaging the can with the fluxing 25 brush after which the table descends, is given another forward step, and the can is brought under and then raised into engagement with the soldering devices 75 from which the can passes, if desired, to a fourth 30 operation performed by mechanism supported like the devices 74 and 75 on a spindle carried at the back of the machine. It will be seen that with this machine the plurality of operations are carried on simultaneously. 35 These operations may be any number desired according to the equipment and adjustment of the machine. The operator has nothing to do but to place the cans on the table and remove the finished cans therefrom. The special utility of the invention 40 adapted as a can capping machine is that it allows the operation to be carried on while the can is full of a liquid or semi-liquid substance. If it is desired to solder 45 the seam thus formed, the soldering operation is also performed with the can in upright position and without danger of spilling its contents.

As shown in Fig. 1 the covers or caps 50 of the can may be provided with annular gutters immediately adjacent to and alongside of the seams for the reception of solder. The form of seam illustrated in Figs. 1, 4 and 5 is particularly adapted to be soldered, while the form of the seam illustrated in Figs. 2 and 6 depends upon the crimping for a tight joint. In some classes 55 of work the crimped seam is sufficiently hermetic while in other classes of work, such for instance as the packing of foods 60 for export the addition of solder is desirable.

While I have herein shown and described 65 the invention as especially adapted to automatic operations on sheet metal cans, it is

apparent that it could be used in the manufacture of various other articles and is in no way limited to the specific work here shown.

Having thus specifically described the preferred embodiment of my invention, what I claim as new and desire to secure by Letters Patent of the United States is:

1. In an apparatus for manufacturing cans, the combination with a frame, of a 75 table capable of sustaining a plurality of cans, means for imparting to the table bodily a back and forth vertical movement and a step by step horizontal movement and devices above the table for operating on the 80 can.

2. In a machine for manufacturing cans, the combination with a frame, of a table capable of sustaining a plurality of cans, means for imparting to the table bodily a 85 back and forth vertical motion and a step by step horizontal motion and a plurality of devices above the table for operating on the cans.

3. In an apparatus for manufacturing 90 cans, the combination with a frame, of a table rotatable horizontally thereon, means for imparting a back and forth vertical motion to the table bodily and a step by step rotary motion and means above the 95 table for operating on the cans.

4. In an apparatus for manufacturing cans, the combination with a frame, of a table rotatable horizontally thereon, means for imparting a back and forth vertical motion to the table bodily and a step by step 100 rotary motion and a plurality of devices above the table for operating on the cans.

5. In an apparatus for the manufacture 105 of cans, the combination of a vertically disposed frame, a rotary table sustained on the lower part thereof, means for imparting to the table a back and forth vertical movement and a step by step rotary movement, and a device sustained by the frame above 110 the table for operating on the cans.

6. In an apparatus for manufacturing cans, the combination of a frame having a vertical column rising therefrom a rotary table mounted at the base of the column, means for imparting to the table a back and forth vertical motion and a step by step 115 rotary motion, and a device sustained by the column above the table for operating on the can.

7. In an apparatus for manufacturing cans, the combination of a frame having a vertical column rising therefrom, a rotary table mounted at the base of the column, means for imparting to the table a back and forth vertical motion and a step by step 120 rotary motion, a device sustained by the column above the table for operating on the can, and means extending through the column for operating said device.

8. In an apparatus for manufacturing cans, the combination of a frame, a vertical column rising therefrom, a table revolvably mounted at the base of the column, means for imparting to the table a back and forth vertical movement and a step by step rotary movement, and a plurality of devices grouped around and sustained by the column for operating on the cans.
10. 9. In an apparatus for manufacturing cans, the combination of a frame, a vertical column rising therefrom, a table revolvably mounted at the base of the column, means for imparting to the table a back and forth vertical movement and a step by step rotary movement, a plurality of devices grouped around and sustained by the column for operating on the cans, and operating mechanism for said devices, the mechanism extending through the column.
15. 10. In an apparatus for manufacturing cans, the combination of a frame, a prime mover mounted therein, a column rising rigidly from the frame, a rotary table mounted at the base of the column, means actuated from said prime mover for imparting to the table a back and forth vertical motion, and a step by step horizontal motion, a plurality of devices grouped around and sustained by the column above the table for operating on the cans, and mechanism for actuating said devices, the mechanism extending through the column and being driven from the prime mover.
20. 11. In an apparatus for manufacturing cans, the combination of a table adapted to carry the cans, means for imparting thereto an up and down vertical motion and a step by step horizontal motion, and a plurality of devices for operating on the cans, said devices being arranged above the table in the path of its horizontal motion, and the vertical motion of the table engaging the cans with said devices and the horizontal motion successively advancing the cans from one of said devices to the other.
25. 12. In an apparatus for manufacturing cans, the combination of a table adapted to carry the cans, means for imparting to said table an up and down vertical motion and a step by step horizontal rotary motion, and a plurality of devices for acting on the cans arranged circularly in the path of rotation of the table, the vertical motion of the table engaging the table with said devices and the step by step rotary motion of the table successively advancing the cans from one of said operating devices to the other.
30. 13. In an apparatus for the manufacture of cans, the combination of a frame, a rigid column rising therefrom, a table mounted to rotate around the base of the column, means for imparting to the table a bodily back and forth vertical motion and a step by step rotary motion, a frame member pro-
- jecting outward from the column above the table and the device carried by said frame member above the table for operating on the cans.
14. In an apparatus for the manufacture of cans, the combination of a frame, a rigid column rising therefrom, a table mounted to rotate around the base of the column, means for imparting to the table a back and forth vertical motion and a step by step rotary motion, a frame member projecting outward from the column above the table a device carried by said frame member above the table for operating on the cans, and means for operating said device, such means extending through the column.
15. In an apparatus for the manufacture of cans the combination of the frame, a rotary prime mover mounted therein, a table mounted to move vertically and to rotate horizontally on the frame, a cam connected to the prime mover, means for communicating the motion of the cam to the table to move the table vertically, a crank driven from the prime mover, a ratchet engaging the table to impart thereto a step by step rotary movement, and an articulate connection between the pawl and the crank to drive the pawl.
16. In an apparatus for manufacturing cans, the combination of a frame, a table adapted to carry the can, said table being mounted to move axially and rotatively a prime mover, devices for imparting axial movement to the table from the prime mover and an articulate connection between the prime mover and the table to impart rotary motion thereto whereby through the medium of said articulated connection the axial movement of the table does not disturb the operation of the means for rotating the table.
17. In an apparatus for manufacturing cans, the combination of a frame, a table adapted to carry the cans, the table having axial and rotative movement, a prime mover mounted in the frame, devices for transmitting the motion of the prime mover to the table to move the same axially a member having sliding engagement with the table to impart thereto its rotative motion, and devices connecting said member with the prime mover and enabling an articulated connection, whereby the vertical motion of the table does not interfere with the means for rotating it.
18. In an apparatus for manufacturing cans, the combination of a rotary table adapted to carry the cans and devices acting on the outer periphery of the table to impart step by step rotative movement to the table whereby idle movement of the table is prevented.
19. In an apparatus for manufacturing cans, the combination with a frame of a ro-

tary table, a member engaged by and sustaining the table, a prime mover mounted in the frame devices for imparting to the said member from the prime mover back and forth vertical motion whereby correspondingly to move the table and devices driven from the prime mover and acting on the table adjacent to its outer periphery to impart to the table rotary movement.

10 20. In an apparatus for manufacturing cans, the combination of a frame, a rotary prime mover mounted therein, a table arranged to move vertically and rotate horizontally on the frame, a non-rotary disk 15 engaged by and sustaining the table, the disk being movable vertically with the table, means for imparting back and forth vertical motion to the disk and table, said means being driven by the prime mover, a crank 20 driven from the prime mover, a member having sliding engagement with the table adjacent to its outer periphery to impart rotary motion to the table and an articulate connection joining the crank and said member.

25 21. An apparatus for manufacturing cans, comprising the combination with the frame of a rotary table mounted thereon, and adapted to carry the cans, said table having 30 a circular slide way, a slide movable in said slide way, a pawl carried by the slide and acting on the table, and means for imparting reciprocal motion to the slide.

22. In an apparatus for the manufacture 35 of cans, the combination with the frame of a table mounted thereon to move vertically and to rotate horizontally, the table having a circular slide way, means for imparting to the table back and forth vertical motion, a 40 prime mover mounted in the frame and operating said means, a slide mounted in said slide way, a pawl carried by the slide, and engaging the table to impart rotary motion thereto, a crank driven from the prime 45 mover, and an articulated connection between the crank and slide for the purpose specified.

23. In an apparatus for the manufacture 50 of cans, the combination with a frame of a vertically movable plate mounted thereon, a prime mover, means for imparting back and forth vertical motion to the plate from the prime mover, a second plate movable vertically on the frame, means for adjustably sus- 55 taining the second plate on the first plate, a table mounted to rotate on and sustained by the second plate and means driven from the prime mover for imparting rotary motion to the table irrespective of its vertical motion.

60 24. In an apparatus for the manufacture of cans, the combination with a frame of a vertically movable plate mounted thereon, a prime mover, means for imparting back and forth vertical motion to the plate from the 65 prime mover, a second plate movable verti-

cally on the frame, means for adjustably sustaining the second plate on the first plate, a table mounted to rotate on and sustained by the second plate, means driven from the prime mover for imparting rotary motion to the table irrespective of its vertical motion, such means comprising a crank and shaft carried with the prime mover, a slide movable on the table and both carried by the slide and engaging the table, and an articulate connection between the crank and slide.

25 25. In an apparatus for the manufacture of sheet metal cans, the combination with a frame, of a plurality of means thereon for operating on the cans, a table adapted to 80 carry the cans and capable of bodily movement back and forth toward and from said means, and step by step advancing movement across the first named line of movement from one of said means to the other and devices for so operating the table, whereby the cans are advanced from one of said means to the other, arrested at each and moved toward and then from it for the purpose of successive operations on the cans.

26. In an apparatus for the manufacture of cans, the combination of a frame, comprising a relatively large base and a hollow column rising therefrom, a revoluble prime mover mounted in the base of the frame, a plate arranged to move vertically on the base of the column, a cam on the prime mover, means actuated by the cam for imparting vertical motion to the plate, a second plate vertically movable on the column, 100 means for adjustably sustaining the second plate on the first plate, a table mounted to rotate around the column and bearing on and sustained by the second plate, a slide movable on the table, a pawl carried by the slide and engaging the table, a crank and shaft mounted on the base of the frame, gearing connecting the shaft with the prime mover and articulate connection joining the crank to the slide, a device for operating on the can said device sustained by the column above the table, a cam on the prime mover shaft, and devices actuated from said cam and extending through the hollow column for actuating the said devices for operating 115 on the can.

27. In an apparatus for the manufacture of cans, the combination with a frame of a spindle having combined rotary and axial movement, a crimping head carried by the spindle, a crimping roller carried by the head, a sectional anvil ring, levers carrying the same, and means actuated by the axial movement of the spindle to move said levers to position the anvil ring against the seam of the can simultaneously with the operation of the crimping roller.

28. In an apparatus for manufacturing cans, the combination of an axially movable spindle and a crimping head carried 130

thereby, a rotary member turning around the axis of the spindle, levers carried by said rotary member, a cam on the spindle engaging the levers upon the axial movement of the spindle, a crimping device carried by the levers and coacting with the crimping head.

In testimony whereof I have hereto put my hand this 15th day of February, 1907.

LEE C. SHARP.
